UNITED STATES PATENT OFFICE.

CHARLES H. BOECK, OF JACKSON, MICHIGAN, ASSIGNOR TO NOVELTY MANUFACTURING COMPANY, OF JACKSON, MICHIGAN, A CORPORATION OF MICHIGAN.

DESIGN FOR A HOT-AIR AND VENTILATING REGISTER FRAME.

SPECIFICATION forming part of Design No. 35,342, dated November 26, 1901.

Application filed August 19, 1901. Serial No. 72,609. Term of patent 14 years.

To all whom it may concern:

Be it known that I, CHARLES H. BOECK, a citizen of the United States, residing at Jackson, in the county of Jackson and State of Michigan, have invented and produced a new and original Design for a Hot-Air and Ventilating Register Frame, of which the following is a specification, reference being had to the accompanying drawings, forming a part thereof.

In said drawings, Figure 1 represents a perspective view of a register-frame, showing my new design; and Fig. 2 is a cross-section taken on the line II II of Fig. 1.

As shown in the drawings, the register-frame is substantially rectangular in form, its four sides each having an inturned flange *a*, which extends along the upper or front edge thereof and together form a support for the usual foraminous top plate, through which the air passes for either heating or ventilating purposes. End portions or extensions *a' a'* of the sides *A* are bent or turned at an angle to the main portions thereof and overlap the adjacent end portions of the sides *A'*, to which they are rigidly secured, thereby forming a box-like structure with open top and bottom. The lower or back edge of each of the sides *A A* is bent or turned inward and upward, forming a rest or stop *a²* along said edge for the slat or valve, rockingly supported adja-

cent thereto within the frame. The lower or back edge of each of the sides *A' A'* is bent or turned inward, thence upward, and thence outward to form the box-bearings *a³*, having a series of perforations therein to receive the end pivots of the slats.

As will be seen, the leading and material features of my design reside in the box-like structure with open top and bottom and with two of its sides or end portions having their lower or back edges bent or turned to form closed box-bearings for the end pivots of the slats, while the other two sides have on their lower or back edges an inturned flange, forming a rest or stop for the sides of the adjacent slats or valves, rockingly supported in said box-bearings.

Having thus described my invention, what I claim as new, and desire to secure by Letters Patent of the United States, is—

The design for a hot-air and ventilating register frame, substantially as shown and described.

In testimony whereof I have signed my name in the presence of two subscribing witnesses.

CHARLES H. BOECK.
